(57) **CLAIM**

The ornamental design for a foot massager, as shown and described.

DESCRIPTION

FIG. 1 is a top front perspective view of a foot massager showing my new design;

FIG. 2 is a bottom front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof; and,

FIG. 8 is a left elevational view thereof.

The letters shown in broken lines are for the purpose of illustrating environmental structure, which form no part of the claimed design.
